TOY LOOM

Samuel Wallach, New York, N. Y., assignor to
Walco Bead Co. Inc., New York, N. Y.

Application July 24, 1947, Serial No. 763,397

7 Claims. (Cl. 139—34)

1

The invention relates to a toy loom which may be used for hand weaving, particularly the weaving of beaded bands and the like which may be made into various articles such as belts, bags, purses and like items. The purpose of the loom is to hold longitudinally extending threads in spaced relation while threading beads thereon in known manner to form a beaded band or other product.

It is an object of the invention to construct a hand loom having a pair of side members or frames which are identical and therefore requires merely one die to produce both side frames of the loom.

Another object of the invention is to construct a loom which is capable of being made into any desired width merely by using longer or shorter spacing bars, bolts and spools or one or more spools.

Other objects of the invention will be more apparent from the following description when taken in connection with the accompanying drawing illustrating the preferred construction of the loom in which:

Figure 1 is a plan view of the loom with the ends of the longitudinal threads secured to one spool and extending over two spacer bars to another spool around which the threads of desired length are wound. A short section of beads are shown threaded thereon.

Figure 2 is a side view of the loom of Figure 1. Figure 3 is an end view of the loom.

Figure 4 is a partial view of the loom showing a rotatable spacer bar.

The hand loom is constructed of a pair of side members or frames 10 which are identical so that only one form is needed and two thereof are used in constructing the loom. With the two side frames which are identical a single die may be utilized to mold the side frame or frames of suitable molding material such as plastic. Each side frame has spaced upwardly extending arms 11 which preferably incline inwardly towards each other. The side frame has a recess or opening, shown as a hole 12 through the side frame, through which a bolt 13 extends and upon which is carried a nut 14. A roller 15 is mounted upon the bolt. The roller forms a spacer for maintaining the two side arms in spaced relation as well as a roll upon which longitudinally extending threads or a finished bead band may be wound.

At the upper end of each arm 11 is a spacer bar recess or socket 18 which receives the end of a spacer bar 19. Any form of spacer bar may

2

be used and any means for keeping the longitudinally extending threads T in spaced relation. The spacer bar particularly shown is held against rotation by the socket 18 being of irregular shape 5 and the ends of the spacer bars being of like shape. The means shown for retaining the longitudinally extending threads T in spaced relation may be a plurality of grooves 20 therein into which the threads T are received. The spacing 10 may be any dimension desired, but for ordinary bead work they would be about $1/16$ inch apart. The recess 18 preferably is of the same shape as the spacer bar 19 which is shown as a half round bar so that the bar is fixed against rotation there- 15 in merely by insertion in the socket or recess. With a bar having grooves only upon one portion of the surface thereof it is desirable to have the bars retained in proper position which is accomplished by the sockets. It is not essential that 20 the spacer bar be of irregular shape in which case it is not essential that it be fixed against rotation. The spacer bar 23 of Figure 4 is not fixed against rotation and hence the thread spacing grooves 24 must take this into account and 25 pass around the complete circumference. The bar in such case preferably would be circular so that rotation of the bar would be feasible. The fixed type of spacer bar however is preferred.

In assembling the loom the spacer bars 19 are 30 inserted in their respective recess or socket 18, a roller 15 is placed in alignment with the holes 12 in the frame and the bolt 13 is projected through the holes in the frame and the roller and the nut 14 is threaded upon the bolt. Tightening 35 of the nut 14 clamps the roller between the side frames against rotation and also rigidly clamps the entire loom together.

A series of longitudinally extending threads T may then be secured to the roller 15 in any suitable fashion such as by a thumb-tack 21, the 40 number of threads corresponding with the width of the beaded or loomed material desired. The threads are made long enough for the length of material or beaded belt desired and the other ends 45 are tied to the thumb-tack on the other roller. Each thread is placed in a groove 20 of the spacer bar and the excess length of thread is rolled up upon one of the rollers. The nuts 14 are then tightened so that the threads are held taut and 50 the frame is locked or clamped together rigidly. The beads are then threaded upon the longitudinally extending threads in known manner until the length between the spacer bars 19, 19 is filled, whereupon the nuts 14 are unloosened and one spool is wound up to wind the beaded

material thereon and the other spool is unwound to provide additional longitudinally extending threads for continuing the weaving or bead looming.

The invention is presented to fill a need for improvements in a loom. It is understood that various modifications in structure, as well as changes in mode of operation, assembly and manner of use, may and often do occur to those skilled in the art, especially after benefitting from the teachings of an invention. Hence, it will be understood that this disclosure is illustrative of preferred means of embodying the invention in useful form by explaining the construction, operation and advantages thereof.

What is claimed is:

1. A hand or bead loom upon which longitudinally extending threads are carried comprising a pair of separate side frames, each side frame having a pair of spaced upwardly extending arms, a socket in each arm, each side frame being a duplicate of the other side frame, a pair of spacer bars each having one end inserted within a socket in one arm of one side frame and the other end inserted in a socket in an arm of the other side frame, means at each end of the loom engaging the side frames to secure the longitudinally extending threads, and means spaced from the spacer bars to clamp the side frames together in spaced relation against the spacer bars and the thread securing means.

2. A hand or bead loom upon which longitudinally extending threads are carried comprising a pair of separate side frames, each side frame having a pair of spaced upwardly extending arms, a socket in each arm, each side frame being a duplicate of the other side frame, a pair of spacer bars each having one end inserted within a socket in one arm of one side frame and the other end inserted in a socket in an arm of the other side frame, means carried by each spacer bar to retain the longitudinally extending threads in spaced relation, a spool mounted at each end of the loom and spaced from the spacer bar, and means to clamp the spools against rotation and secure the side frames together in spaced relation.

3. A hand or bead loom comprising a pair of separate side frames, each side frame having a pair of spaced upwardly extending arms, a socket in each arm, each side frame being a duplicate of the other side frame, a pair of spacer bars each having one end inserted within a socket in one arm of one side frame and the other end inserted in a socket in an arm of the other side frame, a spool mounted at each end of the loom, and means to clamp the spools against rotation and secure the side frames together in spaced relation.

4. A hand or bead loom upon which longitudinally extending threads are carried comprising a pair of separate side frames, each side frame having a pair of spaced upwardly extending arms, a socket in each arm, each side frame being a duplicate of the other side frame, a pair of spacer bars each having one end inserted within a socket in one arm of one side frame and the other end inserted in a socket in an arm of the other side frame, means carried by each spacer bar to retain the longitudinally extending threads in

spaced relation, a spool mounted at each end of the loom with its ends engaging the side frames and spaced from the spacer bars, and means to clamp the side frames together against the ends of the spools in spaced relation.

5. A hand or bead loom comprising a pair of separate side frames, each side frame having a pair of spaced upwardly extending arms, a socket in each arm, each side frame being a duplicate of the other side frame, a pair of spacer bars each having one end inserted within a socket in one arm of one side frame and the other end inserted in a socket in an arm of the other side frame, an opening at each end of each side frame, a bolt extending through the openings at each end of the pair of side frames and spaced from the spacer bars, and a spool mounted upon each bolt and between the side frames whereby the bolts clamp the spools against rotation and secure the side frames together in spaced relation.

6. A hand or bead loom upon which longitudinally extending threads are carried comprising a pair of side frames, each side frame having a pair of spaced upwardly extending arms, a socket in each arm of non-circular shape, each side frame being a duplicate of the other side frame, a pair of spacer bars having ends conforming in shape with the socket and each having one end inserted within a socket in one arm of one side frame and the other end inserted in a socket in an arm of the other side frame, spacing grooves in each spacer bar upon one side thereof, means at each end of the loom engaging the side frames to secure the longitudinally extending threads, and means spaced from the spacer bars to clamp the side frames together in spaced relation against the spacer bars and thread securing means.

7. A hand or bead loom upon which longitudinally extending threads are carried comprising a pair of separate side frames, each side frame having a pair of spaced upwardly extending arms, a socket in each arm of non-circular shape, each side frame being a duplicate of the other side frame, a pair of spacer bars having ends conforming in shape with the socket and each having one end inserted within a socket in one arm of one side frame and the other end inserted in a socket in an arm of the other side frame, spacing grooves in each spacer bar upon one side of the bar, a spool mounted at each end of the loom and spaced from the spacer bars, and means to clamp the spools against rotation and secure the side frames together in spaced relation.
